FABRIC OR THE LIKE

Joseph Kahn, Jr., New York, N. Y.

Application February 2, 1950, Serial No. 7,680

Term of patent 7 years

(Cl. D92—1)

To all whom it may concern:

Be it known that I, Joseph Kahn, Jr., a citizen of the United States, resident of New York, county and State of New York, have invented a new, original, and ornamental Design for a Fabric or the like, of which the following is a specification, reference being had to the accompanying drawing, forming a part hereof.

The figure is a plan view of a fabric, or the like, showing my new design.

A design unit is outlined by broken lines. The design unit is repeated over a fabric or the like as indicated.

I claim:

The ornamental design for a fabric or the like, as shown and described.

JOSEPH KAHN, JR.
